AUTOMATIC SELECTIVE PHONOGRAPH

John R. Mitchell, Dallas, Tex., assignor to The Rudolph Wurlitzer Company, North Tonawanda, N. Y., a corporation of Ohio

Application December 2, 1939, Serial No. 307,300

12 Claims. (Cl. 274—10)

This invention relates to certain new and useful improvements in automatic selective phonographs.

It has for one of its objects to provide a selective phonograph which is so designed and constructed as to automatically play both sides of the record pre-selected for play.

Another object of the invention is to provide a phonograph of this character having means for supporting a plurality of records in such a manner that they can be selectively moved to and from a storing position whereby they are projected to an automatically-adjustable mechanism that presents them to and from a record-play position and further that they can be presented to play either one side or the other of the record, in accordance with the selection made.

Other features of the invention reside in the construction and arrangement of parts herein-after described and particularly pointed out in the appended claims.

In the accompanying drawings:

Figure 1 is a top plan view of a phonograph embodying my invention. Figure 2 is a front elevational view thereof. Figure 3 is an enlarged transverse vertical section taken in the plane of line 3—3, Figure 1, the parts being shown in a record play position. Figure 4 is a view similar to Figure 3 with the parts shown in non-play position. Figure 5 is an enlarged vertical section taken in the plane of line 5—5, Figure 1, showing a record being transferred from the magazine to the record holder and before being deposited on the turntable. Figure 6 is a horizontal section taken substantially in the plane of line 6—6, Figure 2. Figure 7 is a perspective view of the mechanism for controlling the movements of the turntable and tone arm, the parts being in play position. Figure 8 is a fragmentary sectional elevation of the mechanism for transferring the selected record from the magazine to the record holder. Figure 9 is a fragmentary perspective view of the record holder and mechanism for swiveling the same to play either one side or the other of the selected record. Figure 10 is a fragmentary perspective view of the combined record selecting and magazine arresting mechanism showing the cancelling arrangement associated therewith. Figure 11 is a perspective view of the mechanism for controlling the selective horizontal movements of the magazine. Figure 12 is a vertical section taken on line 12—12, Figure 6. Figure 13 is a diagrammatic view of the electric circuit and associated parts governed thereby. Figure 14 is a perspective view of the cam

and associated link for governing the swinging movements of the record holder to and from operative relation with the turntable.

Similar characters of reference indicate corresponding parts throughout the several views.

In its general organization, this automatic phonograph which is primarily designed to selectively play both sides of the records, comprises a turntable which is adjustable vertically to and from a play position, a reproducing unit, a shiftable record magazine disposed at one side of the turntable for adjustment to one or another of a plurality of selective positions, a record holder operable between the magazine and the turntable and adapted for combined vertical and swiveling movements to position one side or the other of the record on the turntable for play, means interposed between the magazine and record holder for transferring the record from the magazine to the holder and vice versa, means for selecting in advance one or more records desired for play, means governed by said selecting means for selectively controlling the swiveling of the record holder in accordance with the record selected, means for elevating the turntable to lift a selected record clear of the record holder into operative engagement with the reproducer, and power driven means for actuating the aforesaid mechanisms in their proper cycle of operation to automatically play the records selected, whether the record-selections chosen be on one side or the other of the records.

Referring now to the drawings, the numeral 35 indicates a supporting platform or frame upon which the working parts of the phonograph are mounted. The turntable 16 is mounted on a vertically adjustable rotatable spindle 17 which extends below the platform and is feathered on a 40 driven sleeve 18 connected by a worm wheel 19 and worm 20 with an electric motor 21. The turntable runs constantly during such time as the motor circuit is closed.

Disposed at one side of the turntable and adapted for selective horizontal adjustment is a record magazine 22 comprising upright, segmental-shaped partitions or plates 23 suitably spaced to provide record-receiving pockets 24 closed at their bottoms and outer sides by walls 50. 25, while their inner sides are open for the discharge and return of the records from and to the magazine as shown in Figures 1, 2 and 5. These partitions are secured at their lower ends to a yoke 26 which extends downwardly through an opening in the platform 15 and is guided

for horizontal movement in a bracket 26^a depending from the underside of the platform.

The adjusting movements of the magazine to record selective positions, prior to transferring the records to a play position upon the turntable, is preferably constructed as follows:

Fixed to the sleeve 18 between the platform 15 and motor 21 is a pinion 27 which is constantly rotating as long as the motor circuit is closed. Adapted to be brought into and out of engagement with this pinion at predetermined times in the cycle of operations is a driven gear 28 journaled on a stud 29 mounted at one end of a horizontally-swinging lever 30 fulcrumed intermediate its ends on a vertical stub shaft 31 journaled in a depending bracket 32 fixed to the platform 15. The actuation of this lever into and out of an operative position is controlled at predetermined times by a pair of solenoids 30^a and 30^b as shown in Figure 6.

Integral with the gear 28 is a pinion 33 which meshes constantly with a gear 34 fixed on the stub shaft 31 immediately below the lever 30, as shown clearly in Figures 6 and 12. On the underside of or constituting a part of the gear 34 is a gear segment or arcuate rack 35 for intermittent engagement with a gear 36 loosely mounted on a stud 37 also secured to the bracket 32. Adapted for coupling or clutching engagement with the gear 36 during a counter-clockwise movement thereof is a spring-pressed pawl 38 pivoted to an arm 38a applied to a notched ratchet wheel 39 mounted below the gear 36 on the stud 37. Connected to the ratchet wheel at 40 is a crank arm 41 which is in turn connected to the yoke 26 to impart a horizontal movement thereto. In clutching engagement with the ratchet wheel 39 is a spring-pressed retractable dog 42 mounted in the bracket 32 and having an upstanding pin 43 thereon which is engaged by a cam plate 44 depending from the underside of the gear 34 and whose leading edge is in advance of the gear segment 35 during a clockwise movement. It will be seen that, when the lever 30 is moved in a direction so that the gear 28 is in mesh with the pinion 27, motion is transmitted to the gear 34, its segment 35 and cam plate 44, the latter engaging the pin 43 of the dog 42 to disengage the dog from the ratchet wheel 39 to free the latter and gear 36 so that the leading end of the segment 35 upon striking the arm 38a moves it and the pawl-engaged gear 36 a fraction of a revolution in a counter-clockwise direction until the teeth of the segment engage such gear 36 at which time the latter and the ratchet wheel 39 are driven by such segment 35 to operate the crank arm 41 and thereupon move the magazine 22 horizontally to a predetermined selected position. The cam plate 44 is of such a length that during such movement of the magazine, it maintains the dog 42 disengaged from the ratchet wheel 39. At a predetermined time in this magazine-adjusting cycle, the cam plate rides off the dog-pin 43 and the dog 42 is automatically restored to latched engagement with the ratchet wheel, and during the balance of the cycle the gear train idly rotates without affecting the ratchet wheel.

The arresting of the magazine to different positions whereby the records pre-selected for play are presented in readiness to be transferred into play position is predetermined by a selector mechanism which is operated by the patron. To this end, I provide a series of selector pins 45 preferably disposed in two rows, one above the

other, one row of pins selectively controlling the presentation of the records on one side and the other row of pins selectively controlling the presentation of the record on the opposite side. 5 These pins are slidingly mounted for horizontal movement in a block 46 secured to the bracket 26^a as seen in Figure 5. At one end each pin has an enlarged head 47 and at the opposite end has a pin 49 which limits its movement to a projected selective position. The projecting movements of these pins to a select position is accomplished by a double-armed trip or actuating member 50 common to all of the pins and fixed adjacent the inner end of a longitudinally shiftable and oscillatory rod 51 mounted in bearing-brackets 52 as seen in Figure 6. At the outer end of the rod is a control knob 53 which is adapted to be grasped by the patron and shifted axially to bring its trip member 50 to a predetermined position opposite a given pair of selector pins 45, and then rocked in one direction or the other to project one or the other of the registering pins to a selective governing position. To insure the patron that he has actuated the correct selector pin, an escutcheon plate 54 is provided with notches 55 arranged in two rows and numbered to correspond to the number of records in the magazine, the even numbers designating, say, the rear side of the record and the odd numbers the front side of the record, viewing the magazine from the front side of the phonograph. Connected to the rod and in operative relation with these notches is a double armed lever 56 which operates in the same manner as the member 50 and when one arm or the other of the lever enters a notch that record has been selected. In the position shown in Figure 6, the eighth record in the magazine and the rear side thereof has been selected for play. 30 Pivoted to a substantially U-shaped bar 57 carried by the magazine-bracket 26 and adapted to travel therewith are upper and lower vertically-swinging dogs 58 which are common to the companion upper and lower rows of selector pins 45 and which, at predetermined times during a selecting cycle, are adapted to engage one or another of the projected pins during the forward travel of the magazine to arrest the latter in a select position. On the rearward movement of the magazine, these dogs are adapted to swing upwardly from contact with the pins and ride over them, a stop pin 59 being associated with each dog to limit its downward swinging movement. 40 When the magazine has been arrested in a selected position, means are provided for transferring that selected record to a record holder whereby it is deposited onto the turntable for play. To this end, I provide a vertically-swinging transfer arm 60 pivoted intermediate its ends at 61 adjacent the rear side of the platform 16 and terminating at one end in a substantially U-shaped portion 62 which is adapted to register with one or another of the magazine-pockets 24 and eject the records therefrom, while its opposite end is adapted to eject a played record from the record holder for transfer back to the magazine, the record rolling by gravity during its transfer. A spring 63 tends to retract the arm into a normal or non-operating position, while in its projected operative position shown in Figure 5, the record is adapted to roll by gravity thereover to the holder means which subsequently places the record onto the turntable. The movement of the arm to eject or transfer a rec-

ord from the magazine by gravity is accomplished by a substantially L-shaped vertically swinging pick-up arm 64 in bearing contact with the arm 60 and fixed at 65 to one end of a rock shaft 66 journaled in the upper end of a hollow post 67 rising from the platform adjacent the magazine 22. Fixed to the other end of the rock shaft is an arm 68 connected by a link 69 to the upper end of a vertically-shiftable pitman 70 slidably mounted within the post and operatively connected at its lower end to the outer end of a vertically-swinging lever 72 pivoted intermediate its ends at 73 at a point below the platform 15. The inner end of the lever 72 preferably terminates in an actuating portion 74 which bears against a cylindrical cam 75 constituting a part of a master cam 76 fixed to the lower end of the stub-shaft 31, as shown in Figures 3 and 4, and adapted to rotate with the gear 34. After the magazine 22 has been selectively positioned in the manner heretofore described, the cam 75 comes into operation to rock the lever 72 in a direction to elevate the pitman 70 and thence rock the pick-up arm 60 vertically into the registering magazine-pocket to eject the record therefrom and direct and transfer it by gravity to the record holder means presently to be described. After the record is played, it is returned from the record holder means to the magazine by effecting a pivoting of the pick-up arm in the opposite direction which lifts the record from the holder means and causes it to roll by gravity to the magazine.

The record holder means is operatively disposed between the turntable and the magazine and is designed to receive the selected records from the magazine and deposit them onto the turntable for playing on one side or the other in accordance with the selection made. To this end, the record holder is preferably in the form of a channel-shaped ring 77 pivoted to swing vertically to and from an operative position over the turntable, as well as to swivel or oscillate to present one side or the other of a record over the turntable, and having approximately half of its peripheral wall, or that portion opposite the magazine, cut away to form a slot or opening 78 for the passage of a record to and from the magazine. It may be stated here that the width of the record-receiving space in the channelled ring is such that when the ring is operatively disposed over the turntable, and the latter is raised to its playing position, the record is free to revolve within the holder without contact therewith, as shown in Figure 3. As shown in Figures 1 and 5, the record-receiving ring 77 is swivelly supported at 79 at diametrically opposite sides and in the axial plane of the turntable in a vertically-swinging frame or carrier 80 fixed at its inner end to a horizontal shaft 81 journaled in suitable brackets 82 rising from the platform 15 to the rear of the turntable. This shaft is adapted to be driven through an arc of approximately 90° to and from a playing position over the turntable and for this purpose may be provided with a chain and sprocket drive 83 connected to a shaft 84 which is adapted to be driven at predetermined times in one direction or the other through the medium of a gear segment 85 and vertically-swinging rack 86 pivoted at 87 below the platform 15 and operatively connected above its pivot to an actuating link or rod 88 having a roller 89 at its free end disposed for engagement with the periphery of a cam 90 mounted on the shaft 81 for shifting the actuat-

ing link in a direction to turn the shaft 81 clockwise, viewing Figures 3 and 4, to bring the record holder from the position shown in Figure 3 to the position shown in Figure 4. For the purpose of turning the shaft 82 in the opposite direction and swinging the holder from the position shown in Figure 4 to that shown in Figure 3, a cam-groove 91 is provided on the cam 90 which is adapted to engage the roller 89 of the link 88 at a predetermined time in the cycle of movement of the cam. A spring 92 may be provided for resisting movement of the holder out of its normal upright position and a rest 93 may be provided to support the holder in its play position over the turntable.

As shown in Figures 1 and 5, the inner end of the pick-up arm 60 terminates alongside the swiveled end of the carrier-frame 80 and its holder 77 and has a pin 60a thereon adapted to extend between such parts and through a notch 60b formed in said holder for engaging the peripheral edge of a record and directing it onto the pick-up for return to the magazine.

When the record holder is swung downwardly over the turntable, the latter is below and spaced from the record, and means are provided for raising the turntable to a height whereby the record is picked up from supporting engagement with the holder-ring 77 and deposited on the turntable for play, with the record free to revolve within but out of contact with the holder. To this end the turntable-spindle 17 rests at its lower end on one arm of a vertically-movable bell crank 94 pivoted at 95 to a post 96 extending below the platform 15. The other arm of a bell crank is connected by a link 97 to one end of a horizontally-swinging tappet lever 98 pivoted at 99 to an arm 100 radiating from the post 96, the other end of said tappet lever engaging a pin 101 projecting from the underside of the master cam 76. It will be seen that upon rotation of the cam in a clockwise direction, viewing Figure 7, that the pin will encounter the tappet lever 98 and in turn, through the link 97 and bell crank 94, raise the turntable to its proper playing elevation, shown in Figure 3. A spring 102 connected to the bell crank acts as a cushion when the turntable is lowered.

Prior to the raising of the turntable 16 into a play position, the reproducer 103 is swung horizontally so that its needle is directly over the sound groove of the record and then lowered onto the record for play. To this end, the reproducer or tone arm is pivoted at 104 to a horizontally-swinging bracket 105 supported on a sleeve 106 extending downwardly through a hollow post or standard 107 rising from the platform 15. Engaging the tone arm forwardly of its pivot is a spindle 108 which is guided for vertical movement in the sleeve 106 and rests at its lower end on the hub of a two armed adjustable member 109 supported at the outer end of a vertically-swinging rock lever 110 pivoted intermediate its ends at 111 and having an upward-extending lug 112 at its inner end for engagement with a recess 113 in the underside of the master cam 76. At a predetermined time in the rotation of the cam the rock lever 110 is displaced vertically by reason of the lug 112 entering into the recess 113 to in turn lower the spindle 108 from contact with the tone arm and allow it to drop by gravity onto the record about its pivot 104 during a selecting cycle. During the playing of the record the cam 76 is at rest and the lever-lug 112 remains in the recess,

so that upon completion of a record-play a reversal of the movements just described takes place and when the cam is again rotated, the lever is rocked to normal position and the tone arm elevated clear of the record.

The horizontal movement of the tone arm, after play, to a normal non-play position at one side of the turntable immediately after the tone arm has been raised from contact with the record, is initiated by the master cam 76 through the medium of a depending lug 114 in contact with the cam and disposed at one end of a horizontally-swinging lever 115 pivoted intermediate its ends at 116 and having its other end engaging an abutment bar 117 extending between one arm 118 of the two-armed member 109 and a crank arm 119 fixed to the lower end of the sleeve 106, as shown in Figure 7. After the record has completed play, the cam is set in motion as previously described to rock the lever 115 in a direction so that its outer end engages the abutment bar 117 and swings the tone arm to one side of the turntable. A leaf or flat spring 120 disposed in the path of travel of the abutment bar 117 serves to swing the tone arm into a play position over the record immediately after the lever 115 is actuated by the cam 76 away or free from contact with such bar.

Means are provided for controlling the swiveling movement of the record holder or ring 77 about its trunnions 79 to present one side or the other of the selected record into play position upon the turntable. The swiveling movement of the holder in one direction or the other takes place during the vertically-swinging movement of the holder toward and from the turntable and is through an arc of 180°, being accomplished by a bevel gear 121 fixed to the inner holder-trunnion 79 and meshing with a like gear 122 constituting a part of a rock arm 123 freely mounted to turn on the shaft 81 and having a lug or shoulder 124 at its free end for latching engagement with a laterally-swinging spring-urged pawl 125 pivoted to one end of a lever 126 fulcrumed intermediate its ends at 127. The other end of this lever is operatively associated with a pair of opposing solenoids 128 and 129 for shifting said lever into and out of latching engagement with the shoulder 124. When the solenoid 128 is selectively-energized to play one side of a given record, it actuates the lever 126 in a direction to bring its pawl 125 into latching engagement with the lug 124 of the arm 123, as shown in Figure 9. It will be seen that, when the arm 123 is held from rotation by the pawl 125, the bevel gear 121 carried by the holder will ride over the companion gear 122, during the lowering of the holder, to swivel the holder about its trunnions through an arc of 180°, and thereby expose the chosen side of the record for play. When the arm 123 is unlatched from the lever 126, as when the companion solenoid 129 is energized when selecting the opposite side of the record for play, said arm will turn with the shaft 81, thus performing no swiveling action to the record holder during its lowering and raising movements.

During the selecting cycle of operations, that is, the adjusting movement of the record magazine 22 to a given record-selecting position, the transfer of the selected record from the magazine to the holder-ring 77, the deposit of the record in the holder-ring to a position over the turntable to play one side or the other of the record, the elevating movement of the turntable 16 into engagement with the record to be played, and the horizontal and vertically-swinging movement of

the tone arm into playing engagement with the starting groove of the record—the gear train and cam elements are in driving engagement with the motor-pinion 27 so that the several parts of the record-selecting mechanism are automatically actuated in predetermined sequence. When these various parts are in readiness to play the selected record, then the gear train and cam elements are automatically disconnected from driving engagement with the motor-pinion and remain at rest during the playing of the record. After the playing of the record has been completed, then means are provided, which are governed by the tone arm, for again automatically connecting the gear train and cam elements into driving engagement with the motor-pinion to cause a reversal of the cycle of operations for returning the played record to the magazine and restoring the other parts to initial position, after which the same cycle of operations is continued for playing the next selected record. The automatic clutching and unclutching of the gear train and cam mechanism of the record-changing mechanism at predetermined times may be controlled electrically by means which are preferably constructed as follows:

Referring to Figure 13 which shows the electric circuit and associated parts of the record changer mechanism governed thereby, the motor 21 is connected to the lead wires 130 and 131 of a source of power, and a switch 132 is included therein for controlling the starting and stopping of the phonograph, and in this connection the switch may be manually operated or it may be coin-controlled in any approved manner. The solenoid 30a and the solenoid 30b are adapted to be energized at predetermined times to automatically shift the lever 30 in one direction or the other to bring the gear 28 into or out of driving engagement with the motor-pinion 27 and for this purpose the solenoid 30a which governs the shifting of the lever 30 in a direction to engage the gear 28 with the pinion 27 is controlled by switches 133 and 134, respectively, the switch 133 having one of its terminals connected by a wire 135 with one end of the coil of the solenoid 30a, the other end of such coil being connected by a wire 136 with the lead wire 130, while the other terminal of said switch 133 is connected by a wire 137 with one of the blades 138 of the switch 134. This last-named switch includes a movable blade 139 operatively associated with the companion solenoid 30b, and an intermediate fixed blade 140 which is connected to the lead 131. Leading from the blade 139 of the switch 134 is a wire 141 which is connected to one of the terminals of an associated switch 142, a companion terminal thereof being connected by a wire 143 with one end of the coil of the solenoid 30b, the other end of the coil of the latter being connected to the wire 136 leading to the lead wire 130. The respective movable blades 138, 139 of the switch 134 are controlled by the movements of the lever 30 in one direction or the other, and to this end such lever is provided with a switch-controlling element 144 which is bifurcated at its free end to provide projections 145 and 146 disposed in the path of the respective switch elements 138 and 139 to govern their opening and closing positions, respectively, with the intermediate element 140 of said switch 134. When the phonograph is in playing position, the lever 30 is in the position shown in Figure 6, with the gear 28 out of driving engagement with the motor-pinion 27 and the switch-blade 138 in contact with the switch-

blade 140, while the companion switch-blade 139 is open so that the circuit of the solenoid 30a is ready to be closed when the switch 133 included in the circuit thereof is closed. This switch 133 is normally open and is adapted to be closed when the tone arm 103 reaches the end of play of a record through the medium of a horizontally swinging arm 141 which turns with the horizontally swinging movement of the tone arm and which is provided at its outer end with a projection 148 disposed in the path of the switch 133 so that when the tone arm reaches its inward position, said projection will close the switch 133 and thereby complete the circuit which will effect the energization of the solenoid 30a and automatically cause the lever 30 to be rocked to the position shown in Figure 13, and wherein the gear 28 is in driving engagement with the motor-pinion 27 to thereby cause the operation of the record changing mechanism to restore the played record back to the magazine as well as to effect the movement of the tone arm outwardly to a position at one side of the turntable. In this position of the lever 30, the switch-controlling element 144 has caused the switch-blade 138 to be opened and the companion switch-blade 139 to be moved in switch-closing engagement with the switch terminal 140 to partly prepare the circuit of the companion solenoid 30b for closing when the tone arm has been again brought into playing engagement with the next record selected for play. The complete establishment of the circuit for rendering the solenoid 30b operative to actuate the lever 30 in the direction to disengage the gear 28 from the motor-pinion 27 takes place when the switch 142 is closed. The closing of this switch is controlled during the vertical movement of the tone arm onto the record, and for this purpose the two-armed member 109 has an arm 149 which is adapted to register and overlie the upper terminal of the switch 142 when the tone arm is in proper register with the starting groove of the record, so that when the tone arm is caused to be lowered by the cam-governed lever 110, said arm 149 will be lowered and accordingly close the switch 142 which will thereby close the circuit through the solenoid 30b and automatically disconnect the record changer drive mechanism from the motor-pinion 27.

The circuit for selectively governing the energization of one or the other of the solenoids 128, 129 to in turn selectively present one side or the other of a record for play includes a switch unit 150 which is carried by the magazine 22 and which in one of two positions governing the selective side of the record to be played controls the closing of the circuit including the solenoid 128 to play such side of the record selected, and which is operatively disposed for actuation to the other of its selective governing positions by one or another of the projected selector pins 45 in a given row, say, the lower row, so that when such switch unit is actuated by contact with a projected selector pin in the lower row it will automatically shift the switch to such other position to control the circuit of the solenoid 129 to insure the playing of the record on the other side selected. This switch unit may be in the form of a mercury switch which is pivoted for vertically swinging movement lengthwise of the row of selector pins to the depending yoke 26 of the magazine 22, and which terminates at its upper end in a trip arm 151 arranged to engage any projected selector pin in the lower row of pins for rocking the switch unit from one normal switch- 75

5 closing position to the other switch-closing position. A spring 152 connected to the switch arm 151 normally urges the switch 150 to a position for energizing the solenoid 128, while in its other or pin-tripped position it closes a circuit to the companion solenoid 129. As shown in Figure 13 of the drawings, the normally closed switch contacts A of the mercury switch are included in a circuit including a wire 153 leading from one of the contacts and connected to one end of the coil of the solenoid 128 and a wire 154 connected to one of the terminals of a transformer 155, the other terminal thereof being connected by a wire 156 to the companion switch contact. One terminal of the other set of switch contacts B of the mercury switch is connected to the transformer-connected wire 156 having a branch 157 leading to one end of the coil of the companion solenoid 129, the other end of such coil being connected by the wire 154 with the companion switch terminal. Normally the mercury switch is held by the spring 152 in a position closed across the contacts A wherein the circuit is completed through the solenoid 128 to effect the latching of the lever 126 with the gear-arm 123 so as to compel a swiveling movement to the record holder ring 11 during the record-selecting operation so as to play the front side of the record, that is, the side of the record which faces the patron when standing at the front of the machine (Figure 2). The playing of the records on the front side is governed by the top row of selector pins, the trip arm 151 of the switch 150 clearing such row of pins. When any one of the lower row of selector pins is projected, they are in the path of travel of the trip arm of the mercury switch so that when the magazine is arrested at a selective station the switch is tripped to the position shown in Figure 13, wherein the switch is closed across the contacts B to effect the energization of the solenoid 129 and accordingly shift the lever 126 to a position to unlatch it from the gear-arm 123 and allow the holder-ring 11 to merely swing downwardly without a swiveling action to present the rear side of the record, that is, the side of the record facing away from the patron when standing at the front of the machine.

40 At a predetermined time in the cycle of record-changing operations, say, at the end of play of a given record, a means is provided for cancelling the selector pin companion to that played record. For this purpose, a pair of upper and lower cancelling solenoids 158 and 159 are mounted on the depending magazine-yoke 26 and are disposed common to and in opposing relation to the companion rows of selector pins 45, so that upon the energization of a given solenoid its plunger causes the retraction or restoration of the aligned selector pin to its initial non-selecting position. One end of the coil of the upper solenoid 158 is connected by a wire 160 with the transformer 155 while the other end of such coil is connected by a wire 161 to the terminal 162 of a normally open switch, such terminal being disposed along the path of selective travel of the selector pin actuating member 50, the other terminal 163 of such switch being borne by the top portion of said actuating member to effect the closing of this switch when the selector rod 51 is rocked to the right viewing Figures 5 and 13. The movable switch terminal 163 is connected by a wire 164 to one terminal of a normally-open second switch 165, the other terminal thereof being connected by a wire 166 with the transformer. The lower solenoid 159 has one end of its coil connected by a wire 167 to the

transformer 155 while the other end of the coil is connected by a wire 168 to one terminal of the switch 165. The latter is disposed adjacent the cam 76 and at a predetermined time after the playing of a record, a pin 169 on this cam encounters and momentarily closes this switch 165 to close the circuit of the solenoids 158 and 159 to effect the cancelling operation. When the selector rod is set with its pin-actuating member 50 rocked to the right, as when selecting the front side of a record for play, the alining selector pin 45 is not only projected to a select position but the switch 162, 163 is closed to place the cancelling circuit including the solenoid 158 in readiness to be completely established by the closing of the switch 165.

I claim as my invention:

1. In an automatic phonograph, a turntable, a magazine for supporting a plurality of records mounted for adjustment to a plurality of record-selecting positions, a swinging carrier operable between the turntable and the magazine for receiving a record from the latter and transferring it to playing relation to the former, means for moving said magazine to different positions of selective adjustment to bring one or another of the records into registering relation with said carrier, and movable means disposed between said magazine and said carrier for operative engagement with a record to transfer and direct it from the magazine to the carrier and from the carrier to the magazine, said means consisting of a vertically swinging arm pivoted intermediate its ends and over which a record is adapted to roll during its transfer and having portions at its ends in registering relation with said magazine and said carrier.

2. In an automatic phonograph, a turntable, a magazine for supporting a plurality of records mounted for adjustment to a plurality of record-selecting positions, a combined swinging and swiveling carrier operable between the turntable and the magazine in side by side relation to and for receiving a record from the latter and transferring it to playing relation to the former to play one side or the other of the record, drive means connected to said carrier for controlling its swinging and swiveling movements, means for moving said magazine to different positions of selective adjustment to bring one or another of the records into registering relation with said carrier, and vertically-swinging means disposed in bridging relation between said magazine and said carrier for operative engagement with a record to transfer and direct it from the magazine to the carrier and from the carrier to the magazine, said transfer means being pivoted between the magazine and the carrier and having its end portions in operative record-engaging relation to such parts, respectively.

3. In an automatic phonograph, a turntable, a magazine for supporting a plurality of records mounted for adjustment to a plurality of record-selecting positions, a swinging carrier operable between the turntable and the magazine in side by side relation to and for receiving a record from the latter and transferring it to playing relation to the former, means for moving said magazine to different positions of selective adjustment to bring one or another of the records into registering relation with said carrier, vertically-swinging means disposed transversely between said magazine and said carrier for operative engagement with a record to transfer and direct it from the magazine to the carrier and from the carrier to

the magazine, said transfer means being pivoted between the magazine and the carrier and having its end portions in operative record-engaging relation to such parts, respectively, for ejecting a record from the magazine or the carrier and causing it to roll by gravity to the carrier or the magazine, a driven mechanism operatively connected to said foregoing elements for actuating them in predetermined sequence to present a record for play and restore it to the magazine after play, and means associated with said driven mechanism for governing the same.

4. In an automatic phonograph, a turntable, a magazine for supporting a plurality of records mounted for adjustment to a plurality of record-selecting positions, a swinging carrier operable between the turntable and the magazine in side by side relation to for receiving a record from the latter and transferring it to playing relation to the former, means for moving said magazine to different positions of selective adjustment to bring one or another of the records into registering relation with said carrier, vertically-swinging means disposed transversely between said magazine and said carrier for operative engagement with a record to transfer and direct it from the magazine to the carrier and from the carrier to the magazine, said transfer means being pivoted between the magazine and the carrier and having its end portions in operative record-engaging relation to such parts, respectively, for ejecting a record from the magazine or the carrier and causing it to roll by gravity to the carrier or the magazine, a drive mechanism operatively connected to said foregoing elements for actuating them in predetermined sequence to present a record for play and restore it to the magazine after play, a shiftable means associated with said drive mechanism for governing the same, and means for automatically actuating said shiftable means at predetermined times to govern bringing a record into and out of playing position.

5. In an automatic phonograph, a turntable, a vertically-swinging, record holder frame disposed at one side of said turntable for movement to and from a record-playing position over the turntable, means operatively connected to said frame for swinging it to and from such position, a record holder swivelly supported within said frame to present one side or the other of the record for play, and a driving connection between said frame-swinging means and said record holder for governing the swivelling movements of the latter during the swinging of the frame.

6. In an automatic phonograph, a turntable, a vertically-swinging, record holder frame disposed at one side of said turntable for movement to and from a record-playing position over the turntable, means operatively connected to said frame for swinging it to and from such position, a record holder swivelly supported within said frame to present one side or the other of the record for play, a driving connection between said frame-swinging means and said record holder for transmitting a swivelling motion to the latter when said frame is swung in one direction or the other, and means operatively connected to said driving connection for rendering it operative or inoperative to swivel the record-holder during the swinging of said frame.

7. In an automatic phonograph, a turntable, a vertically-swinging, record holder frame disposed at one side of said turntable for movement to and from a record-playing position over the turntable, means operatively connected to said

frame for swinging it to and from such position, a record holder swivelly supported within said frame to present one side or the other of the record for play, a driving connection between said frame-swinging means and said record holder for governing the swivelling movement of the latter during the swinging of the frame, said connection comprising meshing gears applied to the swinging axis of said frame and to the swivelling axis of said holder, and means operatively associated with one of said gears for releasably latching it against rotation.

8. In an automatic phonograph, a turntable, a rock shaft disposed at one side of said turntable at right angles to the turntable axis, a vertically-swinging frame fixed to said rock shaft for movement to and from a position overhanging the turntable, a record holder swivelly supported in said frame and having trunnions journaled in the diametrically opposite sides of such frame and at right angles to said rock shaft, means for rocking said shaft in one direction or the other, and a driving connection interposed between one of said holder trunnions and said rock shaft for governing the swivelling movements of the holder.

9. In an automatic phonograph, a turntable, a rock shaft disposed at one side of said turntable at right angles to the turntable axis, a vertically-swinging frame fixed to said rock shaft for movement to and from a position overhanging the turntable, a record holder swivelly supported in said frame and having trunnions journaled in the diametrically opposite sides of such frame, means for rocking said shaft in one direction or the other, a gear loosely mounted on said rock shaft, a second gear fixed to the adjoining holder-trunnion and meshing with said first-named gear, and means releasably engageable with said first-named gear for holding it against rotation to cause a swivelling movement of the holder during a vertically-swinging movement of the holder-frame.

10. In an automatic phonograph, a turntable, a rock shaft disposed at one side of said turntable at right angles to the turntable axis, a vertically-swinging frame fixed to said rock shaft for movement to and from a position overhanging

the turntable, a record holder swivelly supported in said frame and having trunnions journaled in the diametrically opposite sides of such frame, means for rocking said shaft in one direction or the other, a gear loosely mounted on said rock shaft, a second gear fixed to the adjoining holder-trunnion and meshing with said first-named gear, a member radiating from said first-named gear to turn therewith, and a latching member selectively movable into and out of operative engagement with said gear member.

11. In an automatic phonograph, a turntable, a rock shaft disposed at one side of said turntable at right angles to the turntable axis, a vertically-swinging frame fixed to said rock shaft for movement to and from a position overhanging the turntable, a record holder swivelly supported in said frame and having trunnions journaled in the diametrically opposite sides of such frame, means for rocking said shaft in one direction or the other, a gear loosely mounted on said rock shaft, a second gear fixed to the adjoining holder-trunnion and meshing with said first-named gear, a member radiating from said first-named gear to turn therewith, a latching member selectively movable into and out of operative engagement with said gear member, and selector-actuated means operatively associated with said latching member for governing its movement into and out of latching engagement with said gear member.

12. In an automatic phonograph, a turntable, a vertically-swinging frame disposed at one side of the turntable for movement to and from a record-playing position over the same, a record holder swivelly supported in said frame to present one side or the other of the record for play, motion-transmitting means including a selectively-actuated part connecting said holder with its frame for controlling the swivelling or non-swivelling movements of the holder during the swinging of the frame, selector elements for controlling the playing of one side or the other of the record, and means governed by said selector elements for controlling said selectively-actuated part to render said transmission means operative or inoperative to swivel the record holder.

JOHN R. MITCHELL.
